UNITED STATES PATENT OFFICE.

FRANK D. WARD, OF NEW YORK, N. Y., ASSIGNOR TO SAUVAGE-WARD BRAKE COMPANY, INC., A CORPORATION OF DELAWARE.

SLACK-ADJUSTER FOR RAILWAY-BRAKES.

1,113,720.

Specification of Letters Patent. Patented Oct. 13, 1914.

Application filed July 28, 1913. Serial No. 781,489.

To all whom it may concern:

Be it known that I, FRANK D. WARD, a citizen of the United States, residing in the borough of Manhattan of the city of New York, in the State of New York, have invented certain new and useful Improvements in Slack-Adjusters for Railway-Brakes, of which the following is a specification, reference being had to the accompanying drawings, forming a part hereof.

It has been proposed to construct automatic slack adjusters for railway brakes substantially of a slidable spring-pressed take-up rod and a rack bar movable in one direction only by the take-up rod upon the return of the latter to its normal position after excess travel thereof brought about by slack in the brake rigging, whereby the fulcrum of the brake system is shifted to compensate automatically for such slack. In devices of this character it is necessary to provide adequate means for releasing entirely the brake rigging in order that new shoes may be inserted or other usual repairs and adjustments made. In some instances it may be desirable to have the holding devices releasable by operation of the rack itself and by a simple manipulation necessitating the use of only one hand of the repair man.

It is the principal object of this invention to provide holding devices of the character above referred to and adapted to be employed in connection with automatic slack adjusters of the general type above described which may be released by operation of the rack itself and by a simple manipulation of one of the constituent parts of the slack adjusting devices proper.

A further object is to improve slack adjusters of the rack-bar type generally by increasing their strength and incasing the moving parts more completely than has been possible hitherto.

Other objects will appear hereinafter as this description proceeds, reference now being had to the accompanying drawings for a detailed description of the invention.

In these drawings—Figure 1 is a fragmentary view in side elevation of a part of the wheels and truck of a railway car equipped with the improved slack adjuster. Fig. 2 is a view on an enlarged scale, in side elevation, of the improved adjuster, part of the casing being removed to show the opera-

tive parts of the adjuster which are shown in the positions which they occupy when the brake is applied, the take-up rod being retracted from its normal position of rest within the casing. Fig. 3 is a view taken on the plane indicated by the line 3—3 of Fig. 2 and looking in the direction of the arrows. Fig. 4 is a view, partly in section, taken on the plane indicated by the broken line 4—4 of Fig. 2 and looking in the direction of the arrows, the rack-bar and brake system being shown in full release position.

In Fig. 1 is illustrated in a somewhat conventional manner so much of a railway brake rigging as is necessary for a clear understanding of the application of the improved rack-bar slack adjuster. The brake shoes *a*, *a* are shown as suspended by links *b*, *b* from the car truck (not illustrated) and controlled in their movement by a live lever *c* and a dead lever *d* respectively, these operating levers being inter-connected adjacent their lower ends by the usual bottom rod *c*. During the normal application of the brakes the upper end of the dead lever *d* remains relatively stationary and constitutes a fulcrum about which swing the remaining moving parts of the brake rigging. In the present instance, the upper end of the dead lever *d* is connected through a suitable chain *d'* with a rack-bar *d* horizontally disposed within a suitable casing which may be conveniently formed of two parts *f* and *f'* rigidly secured together as by bolts *f*². It will appear, however, as this description proceeds, that the invention is not to be limited to the character of the casing employed for the moving parts of the slack adjuster, but that casings of other forms than that herein illustrated will lend themselves to the practice of the present invention. The casing composed of the two parts *f* and *f'*, which will be termed generally hereinafter the "inclosing" or "supporting" casing, may be supported directly from the car body (not illustrated) by a suitable two-part clamp *g* engaging trunnions *f*³ formed on the outer side walls of the sections *f* and *f'* of the inclosing casing and adjacent their ends. The other end of the inclosing casing may be pivotally secured to the car body as through links *h*, thus permitting a slight movement of the supporting casing as may be necessary to compensate for strains incidental to the use of the device.

As appears particularly in Fig. 4 it has been deemed desirable to form the rack-bar d^2 of substantially cylindrical form in the interest of strength and for other reasons which will hereinafter appear. However, the form of the rack-bar may be changed also without departing from the spirit of the invention, except that it will be found desirable in practice to provide cylindrical bearing sections therefor in order that it may be rotated readily in its supporting casing, as will be understood. The rack-bar d^2 has formed in it a series of teeth d^3 , the chords of which subtend a central angle of approximately 90° . Coöperating with these teeth d^3 to hold the rack-bar against movement in one direction is a dog i mounted pivotally within a chamber f^4 formed in the side wall of one of the sections f of the supporting casing. The dog i is normally held in engagement with the teeth d^3 of the rack-bar d^2 by a suitable spiral spring j operatively disposed within the chamber f^4 . It will now appear that so long as the dog i is in engagement with the teeth d^3 of the rack-bar d^2 movement of the upper end of the dead lever d to the right, as viewed in Fig. 1, cannot occur.

The sections f and f' constituting the inner closing casing for the sliding rack-bar d^2 are formed to receive also a sliding take-up rod k operatively connected through a chain l' with the upper end of the live lever c and the usual pull rod l , the latter being connected to a suitable source of power. The inner end of the take-up rod k may be partially supported and guided in its movement by a pin k^2 , the ends of which are disposed within suitable longitudinal grooves f^5 formed in the opposite side walls of the sections f and f' of the supporting casing. Pivotally mounted on the pin k^2 within the casing constituted by the sections f and f' is a pawl m , the toe of which normally cooperates with the teeth d^4 of a second rack formed on the rack-bar d^2 , as shown most clearly in Fig. 4. The chords of the teeth d^4 may also subtend substantially a central angle of 90° on the rack-bar d^2 , so about one-half, more or less, of the surface of the rack-bar d^2 is taken up by the two racks formed by the teeth d^3 and d^4 , the rest of the surface of the rack-bar being truly arcuate in outline. In addition to the supporting pin k^2 of the pawl m a second stud m' may be formed integral with or secured to the pawl and have its end resting somewhat loosely in guide grooves or shoulders f^6 also formed in the inner side walls of the sections f and f' of the supporting casing. The inner ends of the grooves or shoulders f^6 are inclined, as at f^7 , as shown best in Fig. 2, so that when the take-up rod k is forced leftwardly, as viewed in this figure, to its extreme position the stud m' , following the

inclination f^7 of the guide grooves f^6 , serves to retract the pawl m from its engagement with the teeth d^4 of the rack-bar d^2 . This movement of the take-up rod k and the pawl m , when the brakes are released, is brought about by a suitable spiral spring n disposed within the casing constituted by the sections f and f' and interposed operatively between one end wall of the casing and the pawl m . 75

When the brake shoes are adjusted properly and there is no slack in the brake system, the pawl m is held out of engagement with the teeth d^4 of the rack-bar d^2 by reason of the position of the stud m' on the inclined portion f^7 of the guide shoulders f^6 . The holding dog i is at this time in engagement with one of the teeth d^3 of the other rack on the rack-bar d^2 . If, now, the brakes be applied by application of power through the pull rod l the upper end of the dead lever d will be held relatively stationary by reason of the engagement of the holding dog i with the teeth d^3 of the rack-bar d^2 while the take-up rod k will be drawn to the right, as seen in Fig. 2, together with the pawl m , against the action of the spiral spring n . The length of the inclined portion f^7 of the guide shoulders f^6 is at least equal to the normal travel of the pull rod l , as measured in linear units, so that, normally, at the instant the brakes are completely applied the stud m' will rest on the lower section of the inclined portion f^7 and the toe of the pawl m will be almost in engagement with the teeth d^4 of the rack-bar d^2 . When the brakes are released the spring n will force the take-up rod together with the pawl m to the left, as viewed in Fig. 2, so that the stud m' will again ride up on the inclined portion f^7 and the pawl be returned to its normal resting position. During this operation the spring n serves as a release spring to move the brakes to their release position. Of course, at this time the rack-bar d^2 maintains its fixed position. If, on subsequent applications of the brakes, slack occurs in the brake system, the take-up rod k will have an excess travel equal to the amount of slack within the brake rigging so that the stud m' will move off of the inclined portion f^7 of the guide shoulders f^6 and the toe of the pawl m will come in engagement with the teeth d^4 of the rack-bar d^2 . Perhaps this excess travel will be sufficient only to move the toe of the pawl m over one of the teeth of the rack-bar d^2 or perhaps this excess travel may cause the toe to move over two or more teeth. At all events when the brakes are again released the engagement of the pawl m with one of the teeth d^4 of the rack-bar d^2 will result in the rack-bar d^2 being moved to the left, as viewed in Fig. 2, under the action of the spiral spring n , until the stud m' again 100

115
120
125
130

rests on the inclined portion f^7 of the guide shoulders f^6 and so retracts the toe of the pawl from engagement with the teeth d^4 . After shifting the rack-bar d^2 to an extent 5 equal to the excess travel of the take-up rod k , in the manner pointed out, the take-up rod continues its movement to the left, as viewed in Fig. 2, a distance equal to its normal travel. The next application of the 10 brakes will find the upper end of the dead lever d shifted to an extent just sufficient to compensate for the slack in the brake rigging so that the pull rod will then have only its normal travel.

15 The operation of the parts above referred to is the same in some respects as that found in some other constructions now known. With the description thus far given, however, the gist of the present invention can 20 now be understood more readily. It will be observed that the free end of the rack-bar d^2 is provided with a depending handle d^5 . If this handle be grasped by the repair man and swung in the direction of the arrow indicated in Fig. 4, the rack-bar will be rotated so that the teeth d^3 will be moved out 25 of engagement with the holding dog i and the toe of the latter will rest on the cylindrical portion of the rack-bar, as shown in full lines in Fig. 4. It will be understood that the rack-bar d^2 will now be free to slide in the direction of release within the 30 inclosing casing so that the brake rigging may be released completely and new brake shoes 35 inserted or other adjustments or repairs made readily.

From the description given it will be evident that a repair man by a simple manipulation requiring the use of one hand only 40 may release the rack-bar from engagement with the coöperating parts of the slack adjuster and simultaneously move the same to a position where the brake rigging will be released completely. The handle returns to 45 proper position for action by gravity, and the holding dog i resumes its engagement with the teeth d^3 . The repair man will then make the necessary repairs leaving the adjustment to be done by the device automatically. The next following application 50 and release of the brakes will serve to move the rack-bar to a position where the upper end of the dead lever will constitute a proper fulcrum for the brake rigging and insure 55 the normal travel of the pull rod.

Modifications in the details of construction and arrangement of parts may be made without departing from the spirit of the present invention, provided such modifications and rearrangements fall within 60 the scope of the appended claims.

I claim as my invention:

1. The combination of a car body, a truck, a brake system comprising a live lever and 65 a dead lever, and an automatic take-up de-

vice mounted on the car body and comprising two rods operatively connected to the dead lever and to the pull rod respectively and relatively stationary holding means engaging the first named of said rods to prevent positively movement thereof in one direction while permitting free movement thereof in the opposite direction, said first named rod being rotatable to be released from the holding means and therefore free to be moved bodily in an axial direction to permit the brakes to be swung from the wheels. 70

2. The combination of a car body, a truck, a brake system comprising a live lever and a dead lever, and an automatic take-up device mounted on the car body and comprising a rack-bar operatively connected to the dead lever, a reciprocable take-up rod operatively connected to the live lever, 80 relatively stationary holding means to prevent travel of the rack-bar in one direction, said means permitting free movement thereof in the opposite direction, the take-up rod being operative after excess travel to 85 shift the rack-bar, and the rack-bar being rotatable to be released from the holding means and therefore free to be moved bodily in an axial direction to permit the brakes to be swung from the wheels. 90

3. The combination of a car body, a truck, a brake system comprising a live lever and a dead lever, and an automatic take-up device mounted on the car body and comprising two rods operatively connected to the dead lever and to the pull rod respectively, a stationary spring-pressed holding dog in engagement with the first named rod and a pawl operatively connecting the two rods, the first named rod being rotatable to be released from the dog and the pawl and therefore free to be moved bodily in an axial direction to permit the brakes to be swung from the wheels. 105

4. The combination of a car body, a truck, a brake system comprising a live lever and a dead lever, an automatic take-up device including supporting means mounted on the car body and comprising a rack-bar and a take-up rod, both slidably mounted in said supporting means, said rack bar being provided with two series of teeth, a pawl carried by the take-up rod, a shoulder being formed on the supporting means and co-operating with the pawl to hold the same 110 out of engagement with the teeth of the rack during normal travel of the pull rod and permitting engagement of the pawl with one series of teeth of the rack upon excess travel of the pull rod, a spring-pressed holding dog carried by the supporting means and in engagement with the other series of teeth on the rack-bar, and means to return the pawl to normal position upon the release of the brakes. 115

5. The combination of a car body, a truck, a brake system comprising a live lever and a dead lever, an automatic take-up device including supporting means mounted on the 5 car body and comprising a rack-bar and a take-up rod, both slidably mounted in said supporting means, said rack-bar being provided with two series of teeth, a pawl carried by the take-up rod, a shoulder being 10 formed on the supporting means and coöperating with the pawl to hold the same out of engagement with the teeth of the rack during normal travel of the pull rod and permitting engagement of the pawl with 15 one series of teeth of the rack upon excess travel of the pull rod, a spring-pressed holding dog carried by the supporting means and in engagement with the other series of teeth on the rack-bar, and means to return 20 the pawl to normal position upon release of the brakes, said rack-bar being rotatable to disengage the respective series of teeth from the pawl and the dog.

6. The combination of a car body, a truck, 25 a brake system comprising a live lever and a dead lever, an automatic take-up device including supporting means mounted on the car body and comprising a round rack-bar and a take-up rod, both slidably mounted in 30 said supporting means, two series of teeth formed on the periphery of said rack-bar and disposed substantially at right angles to each other, a pawl carried by the take-up rod and adapted to engage one series of 35 teeth upon excess travel of the pull rod, a spring-pressed holding dog carried by the supporting means and in engagement with the other series of teeth on the rack-bar, and a spring to return the take-up rod to normal 40 position after release of the brakes, said rack-bar being rotatable within the supporting means to disengage the respective series of teeth from the pawl and the dog.

7. The combination of a car body, a truck,

a brake system comprising a live lever and 45 a dead lever, a two-part casing supported on the car body, an automatic take-up device supported in said casing and including two rods operatively connected to the dead lever and to the pull rod respectively, a 50 chamber formed in the side wall of one of the sections of said casing, a spring-pressed holding dog mounted in the chamber and adapted to engage the first named rod, a 55 pawl supported within said casing on the inner end of the second named rod and operative upon excess travel of the pull rod to connect said two first named rods, and guide shoulders formed on the inner side walls of the sections of the casing and coöperating 60 with said pawl to determine the position of the same.

8. The combination of a car body, a truck, a brake system comprising a live lever and a dead lever, a two-part casing supported on 65 the car body, an automatic take-up device supported in said casing and including two rods operatively connected to the dead lever and to the pull rod respectively, a chamber formed in the side wall of one of the sections of said casing, a spring-pressed holding dog mounted in the chamber and adapted to engage the first named rod, a 70 pawl supported within said casing on the inner end of the second named rod and operative 75 upon excess travel of the pull rod to connect said two first named rods, and guide shoulders formed on the inner side walls of the sections of the casing and coöperating with said pawl to determine the position of the 80 same, the first named rod being rotatable to release it from the dog and the pawl.

This specification signed and witnessed this 24th day of July A. D. 1913.
